UNITED STATES PATENT OFFICE.

VAUX OWEN, OF ATLANTA, GEORGIA.

FASTENER.

Application filed May 20, 1925. Serial No. 31,704.

This invention relates to improvements in fastening devices and has particular reference to means for fastening papers in files.

An important object of the invention is to provide a fastener adapted to secure any number of papers in a file folder so as to avoid projection of the fastening means outside of the folder.

A further object of the invention is the provision of a fastener of this character whereby adjacent file folders will be prevented from engagement with the fastening device so as to tear the files and permit each individual folder to be readily withdrawn from the filing cabinet.

A still further object of the invention is to provide a fastening device which is of simple yet durable construction and can be placed upon the market at a very low cost.

Other objects and advantages of this invention will become apparent as the description progresses.

In the accompanying drawing forming a part of this specification and in which like numerals are employed to designate corresponding parts throughout the same:

Figure 1 is a top plan view of a folder showing the device constructed in accordance with my invention mounted thereon,

Figure 2 is a partial end elevation showing the device in operative position and in engagement with a file folder and papers therein,

Figure 3 is a top plan view of the same,

Figure 4 is an enlarged perspective view of a portion of a piercing element used in connection with my device,

Figure 5 is a perspective view of the entire piercing member, and

Figure 6 is an end elevation of the device shown in Figure 5.

It is well known that the fastening devices commonly employed for securing correspondence papers and the like in file holders necessarily require that a portion of the fastener extend outside of the folder, usually from the rear. This feature is very objectionable as the folders are usually filed in a comparatively close manner in the filing cabinet and it is difficult to withdraw one of these folders without also withdrawing a number of others or damaging the adjacent folders. My invention resides primarily in the provision of a fastening device adapted to secure the papers within the file folders so as to obviate any projection which would

interfere with the withdrawal of the adjacent folders.

Referring now more particularly to the structure embodying my improved fastener and the drawings wherein the preferred example is shown for the purpose of illustration, the numeral 10 generally designates a conventional type of file folder usually constructed of durable paper and of rectangular formation. These folders are folded on a central vertical line, shown dotted in Fig. 1 and indicated by the numeral 11, so as to enclose a number of sheets of paper indicated at 12 providing means for separately filing correspondence of a particular designation.

My improved device embodies a base member 13, preferably of circular formation and constructed of cloth material, sufficiently durable to withstand the usage of this purpose. This base member is secured upon the inner side of the back sheet of the folder by means of adhesive or any desirable manner. Secured to the central portion of the base member 13 is a flexible connecting member or cord 14 which may be in the general form of a shoe lace. One end of this cord is secured to the base member 13 by adhesive, sewing, or in any suitable manner while attached to the other end is a suitable piercing member generally indicated by the numeral 15. This piercing member embodies a longitudinal shank of tapered formation 16 provided on one end with a fine point 90 so as to readily pierce paper sheets. The opposite end of the shank 16 is somewhat enlarged and carries a slit sleeve 18 preferably formed at an angular inclination to the shank. This sleeve 18 embraces the free 95 end of the cord 14 and is tightly secured thereon, preferably being crimped so as to obviate the possibility of pulling the piercing member from the cord.

It is obvious from the foregoing description that my improved fastener will be disposed entirely within the file folder 10 without the formation of any projections on the outside of the folder.

In use, the fastener would be secured to 105 the inner side of the folder in the aforementioned manner and the sheets of correspondence paper or the like secured in position by passing the piercing member through the paper adjacent its upper edge and drawing the cord through the opening formed 110 therein. After the paper or papers have

been inserted upon the cord they are firmly thrust against the back of the folder and the piercing member brought around in a semi-circular loop to penetrate the cord immediately above the paper, that is, on the side of the paper opposite the folder back. In this way the sheet will be retained firmly against the back of the folder and held against removal by the position of the piercing member which is retained in position mid-way through the cord, as shown to advantage in Figure 3. It is clearly apparent that additional sheets may be readily placed in the folder by removing the piercing member from the cord and inserting the sheet in the manner previously described, and inserting the piercing member in the cord in a slightly elevated position.

It is to be understood that the form of my invention herewith shown and described is to be taken as the preferred example of the same, and that various changes in the shape, size and arrangement of parts may be resorted to without departing from the spirit of the invention or the scope of the subjoined claims.

Having thus described my invention, I claim:

1. A fastening device comprising, in combination, a base member adapted to be secured within a file folder or the like, a flexible cord having one end secured to the base member, a piercing member including a tapered shank provided on one end with a fine point, and a slit sleeve formed in angular relation to the shank on the opposite ends thereof, the said sleeve being adapted to firmly engage the free end of the cord. 30 35

2. A fastening device comprising, in combination, a base member, a flexible cord having one end secured to the said base member, a piercing member including a shank tapered to a fine point, and a sleeve in an angular position relative to the said shank adapted to firmly engage the free end of the flexible cord, the said piercing member being arranged so as to permit the same being doubled over so as to pierce the cord at its upper projecting end adjacent the uppermost binding sheet. 40 45 50

In testimony whereof I affix my signature.
VAUX OWEN.
